DOOR LATCH

Filed March 26, 1926

UNITED STATES PATENT OFFICE

ROLLO MARPLE OF CHARLOTTE, MICHIGAN, ASSIGNOR TO HANCOCK MFG. CO., OF CHARLOTTE, MICHIGAN, A CORPORATION OF MICHIGAN

DOOR LATCH

Application filed March 26, 1926. Serial No. 97,520.

The present invention relates to improvements in latches for vehicle doors and has particular reference to latches of the type which may be actuated from the outside or from the inside of the vehicle and which may be dogged from the inside against being actuated from the outside, so that the occupant of the closed vehicle may dog the latches of all the doors except one from the inside and then lock the remaining door after leaving the vehicle by means of the usual locking key.

The primary object of the invention is to provide a new and improved latch of the above type which is simple, inexpensive and capable of easy and certain operation.

A further object is to provide a novel door latch in which a single means is employed for actuating the latch from the inside and for actuating a dogging means adapted to prevent opening of the door from the outside of the vehicle.

A more specific object is to provide a movable operating member for the inside of the door which in operating in one direction from normal position unlatches the door and which upon actuation in the other direction from normal position serves to lock the door against unlatching by the outside operator.

Another object is to provide a lever construction which directly unlatches the door and directly dogs the latch parts.

Another object is to provide a detent mechanism associated with the inside lever to aid in determining the normal or non-dogging position of the lever whereby to prevent the lever passing readily into dogging position.

Further objects and advantages will become apparent as the description proceeds.

In the accompanying drawings, Figure 1 is an inside view in elevation of a latch constructed according to my invention, the parts being shown in normal position.

Fig. 2 is a view similar to Fig. 1 with the cover plate removed showing the latch in dogged position.

Fig. 3 is a cross sectional view on the line 3-3 of Fig. 1.

Fig. 4 is a fragmentary view with the

cover removed of the latch in unlatched position.

Although the invention is susceptible of various modifications and alternative constructions I have shown in the drawings and will herein describe in detail the preferred embodiment, and it is to be understood that I do not hereby intend to limit the invention to the specific form disclosed but intend to cover all modifications and alternative constructions falling within the spirit and scope of the invention as expressed in the appended claims.

Generally described the latch comprises an inside operating member or plate constituting a lever which may be thrown in one direction from normal position to open the latch and which may be thrown in the other direction from its normal position to dog the mechanism against operation of the outside operator. The plate or lever itself functions directly as a dog for the latch mechanism. For determining the normal position of the operating lever means is provided which exerts an obstructing force to be overcome in passing into the dogging position from the normal position.

Referring to the exemplary embodiment of the invention, the above conditions are effected by providing an operating lever with a handle which is movable with respect to the lever, preferably in a pivotal relation, so that when actuated in one direction from normal position the lever and handle have one position and when actuated in the other direction the lever and the handle have another relation.

In the device of the drawings the latch comprises a flat base plate 10 and a side flange 11. Some of the working parts are enclosed within a space between the base plate 10 and a cover plate 12. The cover plate is rigidly secured to and spaced from the base by L-shaped lugs 13 formed on the cover plate which in part abut the base plate and in part pass therethrough and which are turned over on the opposite side of the base. A latch bolt comprising a relatively thin strip 14 and a thicker attached beveled head 15 is mounted to slide on the base plate, the head

15 projecting through an aperture in the flange 11. Lugs 16 and 17 struck inwardly from the base provide guides for the latch bolt. A spring 18 secured to the base urges 5 the bolt into projected position. On the latch bolt there is formed a lug 19 at the upper edge in a position suitable for retracting the bolt by the rotation of a roll-back 20 pivoted at 21 on the base. One arm of the 10 roll-back has a shoulder 22 thereon which acts on the lug 19 and a shoulder 23 acted upon by a pivoted dog 24 arranged to receive an outside operator and provided with a square opening 25 for that purpose. One of 15 the cover plate lugs 13 serves as a stop for the dog 24.

The roll-back 20 also has another arm which has a shoulder 26 acted upon by an inside operator to unlatch the bolt and also 20 a second shoulder 27 against which a dogging obstruction is placed to prevent operation of the roll-back and hence to prevent unlatching of the door from the outside. A coiled contractile spring 28 is suitably 25 arranged to urge the roll-back into the position shown in Figs. 1 and 2.

A movable member is provided to serve as the inside operator which is so arranged that stop means operates to arrest its motion in a 30 so-called normal position. A movable element associated with said member can be moved relative thereto to clear the stop means, thus permitting further movement of the inside operator beyond normal position.

35 In the present instance, the inside operator comprises a rocking or lever plate designated generally as 30 which is pivoted at 31 to the base 10. The plate has fingers or projections which loosely encompass one arm of the roll-back 20 so as to permit a limited rocking of the plate without affecting the roll-back. One finger 32 acts on the roll-back shoulder 26 to unlatch the bolt, the parts moving from the normal position of Fig. 2 into the unlatched position shown in Fig. 4. The other finger 33 of the lever plate is arranged to be positioned out of the path of the roll-back during the above described unlatching operation but it is further arranged to be moved 45 into the path of the roll-back for dogging the same. These two positions are shown respectively in Figs. 1 and 2. The finger 33 is provided with a straight edge 34 which cooperates with the shoulder 27 of the roll-back 20, said edge 34 being substantially perpendicular to an intersecting radius through the pivot 31. By this construction the force of the roll-back when exerted on the lever 50 plate 30 is radial and hence the plate serves, through the medium of the roll-back to hold the bolt against retraction by the outside operator. By this construction the rocking plate 30 may be directly operated as a lever 55 to unlatch or to dog the bolt according to

which direction it is moved from its normal position of Fig. 1.

In the present instance, the lever plate 30 is provided with a handle 35 carried on an arm 36 pivoted to the plate 30 at a point 37 intermediate the ends of the arm 36. The pivoted arm has a limited range of movement relative to the plate. The end 38 of said arm passes close to pivot 31 of the lever plate thus limiting its motion in one direction, and the end of the arm is arranged normally to abut the upper side of the base lug 16 (Fig. 1). The arm 36 has a normal relation with the plate determined in part by providing an obstructing lug 39 on the plate so that when moved to unlatch the bolt the arm and lever are rigid. The normal position is further determined by a detent mechanism (Fig. 3) comprising a recess 40 in the plate, a hole 41 in the arm, a steel ball 42 to cause the hole and recess to register and a spring 43 pressing the ball into the recess. The spring 43 is a wide leaf anchored in the cover plate 12 as shown at 44 (Figs. 1 and 3).

As a result of the above construction the control handle and arm are movable clockwise from normal position relative to the plate 30 by exerting sufficient force on the handle to move the ball 42 out of its recess against spring 43. This movement is limited by the arm striking the pivot 31. At the same time while in this limiting abnormal position the arm is so arranged that it renders the stop means ineffective to hold the lever plate from entering its dogging position. In the present instance, since the end 38 of the arm has moved to a position to the left of the lug 16 (Fig. 2), the arm is thus free of the lug and the latter no longer serves to limit the clockwise rotation of the combined lever plate and handle. This permits the plate 30 to rock further in a clockwise direction to bring its finger 33 in a position to dog the roll-back 30.

The spring 28 above described is attached so as to urge the lever clockwise and is preferably secured to the arm 36. Thus the spring acting through the arm at all times urges the lever plate 30 in a clockwise direction, at one time limited by the abutment of arm 36 on lug 16 and at another time by the interlocking engagement of the dogging finger 33 of the lever plate 30 and the shoulder 27 of the roll-back 20. When the spring is so attached to the arm, the detent ball mechanism can be omitted, but it is preferably retained, since it assists in determining the normal position of the parts and provides a given force to be overcome in moving the inside control to dogging position.

The device in operation normally occupies the position shown in Fig. 1, the control handle arm extending vertically, dogging finger 33 being positioned out of the path of shoulder 27 of the roll-back 20, and the shoulder 32 on the lever plate being in con-

tact with the shoulder 26 on the roll-back. The control arm 36 is positioned against lug 39 on the plate 30 so that counter-clockwise movement of the handle 35 moves the roll-back to unlatch the bolt. This movement stretches the spring 28 which automatically returns the lever to its normal position. The lever comes to rest in its normal position by the engagement of the end 38 of arm 36 on the top of the stop lug 16 of the base plate.

When it is desired to dog the mechanism against operation from the outside the handle 35 is moved in a clockwise direction from its normal vertical position. In so moving the handle 35 the arm 36 does not at first move about pivot 31 because it rests upon the stop lug 16 which thereby prevents such rotation. In consequence the arm 36 moves pivotally about its pivot 37 on the plate 30. This movement takes place against the spring 28 and also against the spring 43 which normally holds the ball 42 in a position to cause the arm and plate to maintain the normal relation. In the clockwise rotation of the arm 36 about its pivot 37 the end 38 of said arm slides along the lug 16 and near the limit of its motion it slips off the lug 16 permitting the lever and plate to move again as an integral body about the plate or lever pivot 31. This motion carries the dogging finger 33 into dogging relation with the shoulder 27 of the roll-back and thus holds the latter in a fixed position against operation from the outside.

It will thus be seen that I have provided a latch construction which is not only simple in operation but as well, simple in construction. It is clear that other constructions and modifications of the parts may be made which are within the contemplation of the invention, as expressed in the appended claims.

I claim as my invention:

1. A door latch comprising, in combination, a spring-pressed latch bolt, a spring-actuated roll-back arranged to unlatch said bolt, means arranged for actuation by an outside operator to actuate the roll-back, a rocking member actuated from the inside and arranged to be moved in one direction from a normal position to actuate the roll-back and in the other direction from said normal position to dog the roll-back, a handle-arm pivoted intermediate its ends on said rocking member for limited movement, said arm and rocking member in one limiting position acting as a rigid structure when moved to unlatch the bolt, a stop in the path of said arm to prevent the rocking of the plate into dogging position, said stop and said arm being arranged to clear each other on moving the arm relative to the rocking member whereby to permit moving the rocking member into a position to dog the roll-back, and a mechanism operative to hold the arm and

rocking member normally in said rigid relation.

2. A door latch comprising, in combination, a spring-pressed latch bolt, a spring-actuated roll-back arranged to unlatch said bolt, means arranged for actuation by an outside operator to actuate the roll-back, a rocking member actuated from the inside and arranged to be moved in one direction from a normal position to actuate the roll-back and in the other direction from said normal position to dog the roll-back, a handle-arm pivoted intermediate its ends on said rocking member for limited movement, said arm and rocking member acting as a rigid structure in one limiting position when moved to unlatch the bolt, a stop in the path of said arm to prevent the rocking of the plate into dogging position, said stop and said arm being arranged to clear each other on moving the arm relative to the rocking member whereby to permit moving the rocking member into a position to dog the roll-back, and a spring tending to hold said arm in a position to strike the stop.

3. In a door latch of the character described, having a roll-back to unlatch a bolt, an inside operator comprising, in combination, a rocking plate having one part to move the roll-back when rocked in one direction from a normal position and another part to dog the roll-back when rocked in the other direction from said normal position, a handle-arm on said plate for rocking the plate, said arm being pivoted intermediate its ends to said plate for a limited pivotal movement, a spring between the arm and the roll-back tending to hold the arm in one limiting position, stop means arranged to act on the arm at said position to prevent rocking the plate into dogging position, said means being arranged to clear the arm when said arm is moved into its other limiting position, whereby said spring draws the arm and rocking plate into dogging position.

4. In a latch of the character described having a latch moving mechanism, a rocking plate pivoted for motion in one direction to dog the mechanism and in the other direction to actuate the mechanism, said plate being formed to act directly on said mechanism to actuate it and to dog it.

5. In a latch of the character described, a lever member comprising a rocking plate and a handle member pivoted to said plate for limited motion relative to the plate, and a stop means for said plate actuated by the pivotal movement of said handle member to engage and disengage said plate.

6. In a device of the character described, a movable member, an element carried by said member having a limited pivotal connection therewith, a spring acting on said element to move the member, stop means in the path of the movable member arranged for engage-

ment with said element to limit the motion of the member, said element being arranged upon pivotal motion to clear the stop means to permit further motion of the member under the influence of said spring.

7. In a device of the character described, a movable member, an element associated with said member and arranged to have a limited movement relative to said member, 10 a spring tending to move the member, stop means positioned to prevent motion of the member under the influence of said spring, said element being so related to said member and said stop means that relative motion of said member and element renders the stop means ineffective to prevent further movement of the member beyond said stop means.

8. A door latch comprising a roll back, a member adapted on rocking in one direction 20 to operate said roll back and upon rocking in the opposite direction to dog said roll back, resilient means acting to move said member into the dogging position and means normally holding said member out of said dogging position, said means being disengageable when movement of said member into said dogging position is initiated.

9. A door latch having, in combination, a spring pressed bolt, a roll-back, an outside 30 operator for actuating the roll-back and thereby the bolt, and an inside operator comprising an operating arm, a member movable in the operation of said arm and having a part adapted in the movement of said arm 35 in one direction to actuate the roll-back and having a dog adapted in the movement of the arm in the opposite direction to engage said roll-back to hold it against operation by the outside operator, and means acting upon said 40 arm to hold said dog in operative position against movement by the outside operator.

10. A door latch having, in combination, a spring pressed bolt, a roll-back, an outside operator for actuating the roll-back and 45 thereby the bolt, and an inside operator comprising an operating arm, a member movable in the operation of said arm and having a part adapted in the movement of said arm in one direction to actuate the roll-back and 50 having a dog adapted in the movement of the arm in the opposite direction to engage said roll-back to hold it against operation by the outside operator, and a stop with which said arm is adapted to engage in the 55 operative position of the dog to hold the latter against movement by the roll-back.

11. A door latch having, in combination, a spring pressed bolt, a roll-back, an outside operator for actuating the roll-back to withdraw said bolt, and an inside operator comprising a member having an actuating part and a dogging part, said actuating part being adapted in the movement of the member in one direction to operate the roll-back and 60 said dogging part being operable in the

movement of the member in the opposite direction to engage and hold the roll-back against movement by the outside operator, said member also having positively acting means associated therewith to hold the dogging part in operative position.

In testimony whereof, I have hereunto affixed my signature.

ROLLO MARPLE.
